[57] CLAIM

The ornamental design for a simulative toy car, as
shown and described.

DESCRIPTION

FIG. 1 is a top plan view of a simulative toy car showing
my new design;

FIG. 2 is a right side elevational view thereof, the side
opposite being substantially in a mirror image.

FIG. 3 is a front elevational view thereof.

FIG. 4 is a bottom plan view thereof.

FIG. 5 is a cross-sectional view of the body member
taken along the reference line in FIG. 6.

FIG. 6 is a rear elevational view thereof.

FIG. 1

FIG. 3

FIG. 2

FIG. 4

FIG. 6

FIG. 5
